UNITED STATES PATENT OFFICE.

WALTER L. OSWALD, OF NEW YORK, N. Y., ASSIGNOR TO CRANE COMPANY, OF CHICAGO,
ILLINOIS, A CORPORATION OF ILLINOIS.

BOILER FEED APPARATUS.

1,251,092.

Specification of Letters Patent. Patented Dec. 25, 1917.

Application filed September 19, 1916. Serial No. 120,923.

To all whom it may concern:

Be it known that I, WALTER L. OSWALD, a citizen of the United States, residing at New York city, State of New York and county of New York, have invented certain new and useful Improvements in a Boiler Feed Apparatus, of which the following is a specification.

My invention relates in general to boiler feeding apparatus, and has reference more particularly to that type in which a supply of condensate or other feed water is passed to a boiler or tank through the medium of a trap or like device, and wherein it has been the customary practice to provide supplementary devices of a character requiring attention, as feed water pumps or pump governors, with the purpose in view of maintaining the water level in the boiler.

The chief aim of this invention is to improve the construction, and increase the efficiency and utility of apparatus of this character; and has for its principal objects the following: First, to produce an improved form of apparatus in which the supplementary devices, above referred to, are eliminated and wherein the feed water discharge to the boiler is automatically controlled. In other words, the water is fed by the trap to the boiler without requiring any attention whatsoever on the part of an operator when the water-line is below the predetermined level, and trap action in the way of discharging water automatically ceases when the water rises to resume its predetermined level in the boiler. Second; to effect an automatically controlled supply of feed water to the boiler proportionate to the demand for steam, *i. e.*, the load on the boiler. Third; to maintain a more uniform water level in the boiler than heretofore maintained by the employment of the customary supplementary controlling devices; and fourth; to provide a simple and inexpensive automatically controlled feeding system which is positive in operation and which has no involved or intricate mechanism requiring either attention, inspection or adjustment.

These, together with such other objects as may hereinafter appear, or are incident to my invention, I attain by means of the construction illustrated in preferred form in the accompanying drawings, wherein:—

Figure 1 represents a front elevation of

my improved apparatus, the upper portion of the boiler being sectional;

Fig. 2 is a view in perspective of the preferred type of trap forming part of said apparatus; and

Fig. 3 is an enlarged detail in section of the T portion of the trap trunnion.

Referring to the drawings, the letter B designates the boiler provided with the usual fire tubes 6 and having the steam space 7 located intermediate the head 8 and the normal water level indicated by the numeral 9. Mounted in any suitable or convenient manner above the boiler B is a receiver R receiving its supply of condensate or other feed water through the inlet or drip return pipes 10. The letter T in Fig. 1 designates a direct return trap desirably mounted on the head of the boiler, being above the steam space and below the receiver R and operating through its connections with the boiler and receiver to receive a supply of feed water and discharge the same into the boiler at such times as the water line is below the predetermined level, the discharge action ceasing as the water line is again raised to its normal level.

Any return trap or similar device may of course be employed, and in this connection a brief description only is here given of the trap illustrated in the drawings, ifasmuch as the details of its construction are fully set forth in Letters Patent #1,114,141 of October 20, 1914, to which reference may desirably be made.

The trap, as shown, occupies the position when empty or in process of being filled, and comprises a base 11 provided with the connected valve casings 12 and 13 and the boxes 14 and 15, in which are trunnioned the outer ends of the pipes 16 and 17, both valve casings alternately communicating through the pipe 16 with the tank 18 as the latter tilts on its axis. The numeral 19 indicates the customary counterbalance weight pivotally connected with the tank by the rod 20 and fulcrumed on the strap 21 which may be connected with the base 11 in any suitable manner. Secured to the inner ends of the trunnion pipes 16 and 17 by coupling members 22 is a T 23 whose inner portion has a threaded engagement at 23^a with the neck 18^a of the tank and projects therethrough to receive the steam conducting pipe 24, which latter communicates with the pipe 110.

16. This inner portion is also formed with a water conducting opening 25 leading from the pipe 17 to the interior of the tank, said pipe terminating in a branch 17^a provided with the check valves 26 and 27.

5 The numeral 28 designates the water supply or inlet pipe for the trap which has its upper end connected with the lower portion of the receiver and its lower end with 10 the check valve 26; 29 is a discharge pipe connected with the valve 27 and leading from the trap to the boiler; 30 indicates a vent pipe extending from the outlet side of the valve casing 12 to the upper portion of 15 the receiver R and provided with a check valve 31; and 32 designates a live steam inlet pipe having its upper end connected with the inlet side of the valve casing 13 and extending through the steam space of the 20 boiler to have its lower end terminal at the approximate normal water level, indicated in Fig. 1 of the drawings at 9.

The valves in the casings 12 and 13 receive alternate actuating on the tilting of 25 the tank by means of the valve stems, 12^a and 13^a, respectively, which are operated by the levers 12' and 13' suitably fulcrumed and connected with the tank, so that when the tank is filled and drops the vent line 30 is closed and the steam inlet is opened and the live steam entering the tank through the pipe 24 drives the accumulated water out of the tank via the opening 25, pipe 17, and thence through the discharge pipe 29 35 into the boiler. Tilting of the tank in the opposite direction opens the vent line 30 and provides an avenue of escape of the steam in the trap to the receiver, thereby operating to produce a flow of water from 40 the receiver through the pipes 28 and 17 and opening 25 to the tank interior, the pressure gradually diminishing in the tank closes the valve 31 and effects an overbalancing of pressure in the receiver to accelerate this flow to the trap.

45 From the foregoing, it will be apparent that when the water line is at normal the inlet end of the steam conducting pipe 32 is closed off from the steam in the steam 50 space. As the demand for steam upon the boiler lowers the water line to a point below the inlet end of the pipe, the steam in the steam space has a clear avenue of flow to the trap, and in the manner hereinbefore set forth effects a discharge of the tank contents through the pipe 29 to the boiler, the

tank filling and again discharging as often as may be necessary to bring the water line to a predetermined level, whereupon the discharging action of the tank at once ceases. 61 Hence it is obvious that the feeding of the water to the boiler is not only automatically controlled but the supply of feed water to the boiler corresponds to the demand for steam. 65

What I claim is:—

1. In a boiler feed apparatus, the combination of a boiler; a self-contained feed water receptacle having an upper inclosed portion constituting a pressure retaining 70 and water heating chamber for the feed water therein; a steam trap embodying a tilting tank provided with steam and water conducting connections with said boiler and said receptacle; one of said steam conducting connections leading from the tank interior to the pressure chamber of the said receptacle and the other leading from the steam space of the boiler to the interior of the tank and normally closed at its inlet end 80 by the water in the boiler; and valvular means for said connections, part of said means actuatable by the tilting of the tank and the other part pressure actuated; substantially as described and for the purpose 85 set forth.

2. An automatic boiler feed system comprising in combination with a boiler; a self-contained feed water container having a feed water inlet and an upper inclosed portion constituting a pressure retaining and water heating chamber for the feed water entering therein; a steam trap embodying a tilting tank provided with a pressure chamber intermediate the boiler and said container, and having steam and water conducting connections with said boiler and container; one of said steam conducting connections leading from the pressure chamber of the tank to the pressure chamber of said 95 container and the other leading from the steam space of the boiler to the pressure chamber of the tank and normally closed at its inlet end by the water in the boiler; and valvular means for said connections, part of said means tank actuated and another part actuated by the pressure in said 100 pressure chambers.

In testimony whereof I have hereunto set my hand and seal to this specification.

WALTER L. OSWALD. [L. S.]
